US0D1052858S

(12) **United States Design Patent** (10) Patent No.: **US D1,052,858 S**
(45) Date of Patent: ** Dec. 3, 2024

(54) **HALFBOOT**

(71) Applicant: **HERMES SELLIER (Société par actions simplifiée)**, Paris (FR)

(72) Inventor: **Pierre Hardy**, Paris (FR)

(**) Term: **15 Years**

(21) Appl. No.: **35/518,202**

(22) Filed: **Mar. 30, 2023**

(80) **Hague Agreement Data**

Int. Filing Date: **Mar. 30, 2023**

Int. Reg. No.: **DM/228032**

Int. Reg. Date: **Mar. 30, 2023**

Int. Reg. Pub. Date: **Sep. 1, 2023**

(51) **LOC (14) Cl.** 02-04

(52) **U.S. Cl.**

USPC **D2/910**; D2/909; D2/925

CLAIM

The ornamental design for a halfboot as shown and described.

DESCRIPTION

1.1 : Perspective

1.2 : Front

1.3 : Back

1.4 : Right

1.5 : Left

1.6 : Top

1.7 : Bottom

1.8 : Perspective

1 Claim, 8 Drawing Sheets
